No. 818,828.

PATENTED APR. 24, 1906.

R. S. KASSON.

CLUTCH.

APPLICATION FILED JAN. 15, 1906.

UNITED STATES PATENT OFFICE.

RUTGERS STAGG KASSON, OF WILMINGTON, DELAWARE.

CLUTCH.

No. 818,828.

Specification of Letters Patent.

Patented April 24, 1906.

Application filed January 15, 1906. Serial No. 296,077.

To all whom it may concern:

Be it known that I, RUTGERS STAGG KASSON, a citizen of the United States, and a resident of Wilmington, in the county of New-
5 castle and State of Delaware, have invented a new and Improved Clutch, of which the following is a full, clear, and exact description.

This invention relates to clutches.

10 The object of the invention is to produce a clutch which is so constructed as to enable the force transmitted to be very accurately adjusted.

15 The invention is applicable in many connections.

The invention consists in the construction and combination of parts to be more fully described hereinafter and particularly set forth in the claims.

20 Reference is to be had to the accompanying drawings, forming a part of this specification, in which similar characters of reference indicate corresponding parts in both figures.

25 Figure 1 is a longitudinal section through a clutch constructed according to this invention, and Fig. 2 is a cross-section taken on the line 2 2 of Fig. 1.

Referring more particularly to the parts, 30 1 represents a case or barrel which has preferably a conical bore, as shown, presenting a hub 2 at its reduced extremity and a flange 3 at its enlarged extremity. At its large end this case is preferably made with a cylindrical counterbore 4, so that an annular shoulder 5 is presented. The hub 2 is formed with a bore 6, through which passes loosely a shaft 7. This shaft passes into the interior of the case and carries rigidly a cone 8. The 35 hub 2 is provided on its inner side with a bore 9, which communicates with the conical bore 10 of the case. This bore 9 is enlarged with respect to the diameter of the shaft 7, so that a chamber is formed in which a helical spring 11 is placed, as shown. This spring 40 thrusts at its outer extremity against the hub 2, and against its inner extremity I set a washer 12, which lies against the inner extremity of the cone 8. The cone 8 conforms 45 closely to the shape of the interior of the case 1, having a conical body with a cylindrical base or shoulder 14, said shoulder being received in the counterbore 4 and resting adjacent to or against the annular face or shoulder 5, referred to above.

Against the inner or end face 15 of the case 1 I attach a diaphragm 16, which is held in position by means of screw-bolts 17, as indicated, the same passing through a keeper or ring 18 and a cover 19 of circular form, which is placed beyond the ring, as shown. The face 20 of the ring, which lies adjacent to the diaphragm, is preferably beveled or inclined, as indicated. The ring 18 constitutes a distance-piece between the cover and the diaphragm, so that a chamber 21 is formed therebetween. I provide means for introducing into this chamber a fluid, such as water. For this purpose I provide the cover 19 with a hub 22, which is provided with a bore 23, 65 communicating with a corresponding bore in a hollow shaft 24. It should be understood that the inner end face 25 of the cone 8 lies substantially against the diaphragm 16, and, further, that the cover 19 is rigid with the 70 hollow shaft 24.

With the construction described it should then be understood that the shafts 7 and 24 may rotate independently of each other, it being understood, of course, that the cover 80 19, together with the case 1, will rotate with the shaft 24. When it is desired to apply the clutch, a suitable fluid is admitted through the hollow shaft 24 and the bore 23 into the chamber 21, producing a pressure upon the 85 diaphragm 16, exerted in the direction of the cone 8. In this way the diaphragm 16 comes against the face 25 of the cone and seats the cone 8 firmly upon the case 1. In this way a very considerable frictional 90 resistance is developed, which affords means for rotating the cone 8 and the shaft 7 with the shaft 24. The degree of force with which the cone 8 is held against the cover 1 may be very accurately controlled by the pressure 95 of the fluid admitted into the chamber 21. Hence the amount of power which can be transmitted may be accurately controlled. The spring 11 normally holds the body of the cone out of engagement with the case, so 100 that under normal conditions little or no friction is developed. In this connection it should be understood that in practice the parts will be designed and proportioned so that little friction will be developed between 105 the face 25 and the diaphragm. I prefer to make the diaphragm 16 of steel or similar material.

By beveling the inner face of the ring 18 as described above the fluid admitted into 110

the chamber 21 applies itself to a greater area upon the diaphragm and more movement is allowed the diaphragm.

Having thus described my invention, I claim as new and desire to secure by Letters Patent—

1. In a clutch, in combination, a case presenting a substantially conical bore, a cone mounted in said conical bore, a shaft rigidly attached to said cone, a diaphragm attached to said case and lying adjacent to the end of said cone, and means for applying fluid-pressure to said diaphragm.
2. In a clutch, in combination, a case having a substantially conical bore, a cone mounted therein, a shaft rigid with said cone, a diaphragm attached to said case and lying adjacent to the face of said cone, means for applying a fluid-pressure to said diaphragm, and means for normally maintaining said cone out of engagement with said case.
3. In a clutch, in combination, a case having a substantially conical bore and a chamber at the small extremity thereof, a cone mounted in said bore, a shaft rigid therewith, a spring within said chamber tending to hold said cone out of contact with said case, a diaphragm attached to said case and lying adjacent to the large end of said cone, and means for applying fluid-pressure to said diaphragm.
4. In a clutch, in combination, a case having a substantially conical bore, a cone mounted within said case, a shaft rigid with said cone, a diaphragm attached to said case and lying adjacent to said cone, a cover for said

case and forming a chamber on the side of said diaphragm remote from said cone, and means for admitting fluid to said chamber.

5. In a clutch, in combination, a case having a substantially conical bore, a cone mounted in said bore, a shaft rigid with said cone, a cover for said case, a diaphragm between said cover and said cone, a ring between said diaphragm and said cover and forming a chamber, and means for admitting a fluid to said chamber through said cover.

6. In a clutch, in combination, a case having a substantially conical bore and a hub at the reduced extremity thereof, said hub having a bore therethrough, a shaft passing through said last bore, a cone rigid with said shaft and lying within said case, said hub having a chamber formed therein, a spring within said chamber and tending to force said cone away from contact with said conical bore, a cover attached to said case, a diaphragm and a ring between said cover and said case and forming a chamber at said diaphragm on the side remote from said cone, said cover having an opening therethrough, and a hollow shaft rigidly attached to said cover and communicating with said opening to admit a fluid to said chamber.

In testimony whereof I have signed my name to this specification in the presence of two subscribing witnesses.

RUTGERS STAGG KASSON.
